UNITED STATES PATENT OFFICE.

JULIUS MAAS AND STERLING W. SHUTTLEWORTH, OF TAMPA, FLORIDA.

DESIGN FOR A POCKET-LIGHTER-FILLING STATION.

Application filed June 2, 1928. Serial No. 26,985. Term of patent 7 years.

To all whom it may concern:

Be it known that we, JULIUS MAAS and STERLING W. SHUTTLEWORTH, citizens of the United States of America, residing at Tampa, in the county of Hillsborough and State of Florida, have invented a new, original, and ornamental Design for a Pocket-Lighter-Filling Station, of which the following is a specification, reference being had to the accompanying drawing, forming a part thereof.

In the drawing:

Figure 1 is a front perspective view of our design, and

Figure 2 is a rear elevation thereof.

We claim:

The ornamental design for a pocket lighter filling station, as shown.

JULIUS MAAS.
STERLING W. SHUTTLEWORTH.
